UNITED STATES PATENT OFFICE

EUGENE POWELL, OF CONNEAUTVILLE, PENNSYLVANIA.

IMPROVEMENT IN CANE-PRESSES.

Specification forming part of Letters Patent No. 27,830, dated April 10, 1860.

To all whom it may concern:

Be it known that I, EUGENE POWELL, of Conneautville, in the county of Crawford and State of Pennsylvania, have invented a new and Improved Machine for Expressing Juice from Sugar-Cane; and I do hereby declare that the following is a full, clear, and exact description of the same, reference being had to the annexed drawings, making a part of this specification, in which—

Figure 1 is a side sectional view of my invention, taken in the line *xx*, Fig. 1. Fig. 2 is a front sectional view of the same, taken in the line *yy*, Fig. 1. Fig. 3 is a side view of the same.

Similar letters of reference indicate corresponding parts in the several figures.

To enable those skilled in the art to fully understand and construct my invention, I will proceed to describe it.

A represents a frame, which may be of cast-iron, and constructed in any proper way to support the working parts. In the upper part of this frame *A* a cylinder, *B*, is placed, the journals *a* of which are fitted in permanent bearings in the frame *A*.

On the outer end of each journal *a* a toothed wheel, *C*, is placed, and these wheels gear into pinions *D* at the ends of cylinders *D'*, the journals *b* of which are fitted in curved or segment bars *EE*—one at each side of the frame *A*. The bars *EE* rest at one end on ledges or projections *c* on the frame, and the opposite ends rest on taper keys *d* in the frame. The centers of the bars *EE* at their under sides rest on set-screws *e e*, both of which are shown in Fig. 2.

There are five cylinders *D'*, (shown in Figs. 1 and 3,) and it will be seen that they are considerably smaller in diameter than the cylinder *B*. The bars *EE* are by means of the taper keys *d* and set-screws *e e* so adjusted in the frame *A* that the cylinders *D'* will gradually approach nearer the large cylinder *B* from the feed to the discharge end of the machine—that is to say, the cylinder *D'* at the feed end of the machine is farther from the cylinder *B* than any of the others—and the others consecutively approach nearer the cylinder *B*, each cylinder a trifle nearer than the one in front of it, so as to form a passage or space gradually decreasing in height between the cylinder *B* and the cylinders *D'*. This will be fully understood by referring to Fig. 1. The smaller

cylinders, *D'*, are of course parallel with the larger one, *B*, and the former do not quite touch each other, as will be seen by referring to Fig. 1.

At each side of the frame *A* there is secured a semicircular plate, *E'*, and these plates extend down below the upper parts of the ends of the cylinders *D'*, and may be described as forming sides to the space between the large and small cylinders. Both of these plates *E' E'* are shown in Fig. 2.

In the frame *A* there is secured a sheet-metal apron, *F*. This apron extends underneath the cylinders *D'*, and is provided at each side with a side piece, so as to form a basin to receive the juice.

To the feed end of the frame *A* there is secured a transverse plate, *G*, to which tubes *H* are fitted. Any proper number of tubes *H* may be employed. They are placed in a horizontal line, which is directly opposite the enlarged end of the space between the cylinder *B* and the cylinders *D'*, as shown clearly in Fig. 1. The plate *G* covers the feed-entrance to the space above mentioned. The toothed wheel *C* at one side of the machine gears into two pinions, *D D*, of cylinders *D'*, while the wheel *C* at the opposite side of the machine gears into the three pinions *D* of the remaining three cylinders *D'*.

The operation is as follows: The cane (shown in red) is fed by the operator through the tubes *H* into the space between the cylinder *B* and the cylinders *D'*, the former being rotated by any convenient power in the direction indicated by the arrows. The cane, in passing between the cylinder *B* and cylinders *D'*, is subjected to a series of pressures corresponding in number to the number of cylinders *D'*, each pressure being gradually increased in consequence of the gradually-decreasing space between the cylinders *D'* and the cylinder *B*, as previously described. The juice, in consequence of this arrangement, will be fully expressed from the cane and will pass down into the basin *F*. The plate *G'* prevents the juice from being forced out at the feed end of the machine—a contingency which would otherwise occur. This plate, of course, it will be seen, involves the necessity for the use of tubes *H*, or their equivalents, in order to facilitate the feeding of the cane into the space between the cylinders. The semicircular plates *E' E'*

prevent the cane from escaping laterally out from the machine or from between the cylinders, and thereby insures a full and perfect action of the cylinders upon it. The juice escapes from the basin F through any proper opening and falls into a suitable receptacle prepared to receive it.

Having thus described my invention, what I claim as new, and desire to secure by Letters Patent, is—

The combination, with the basin F, plates E' E', cylinders D', and cylinder B, of the curved plate G, when provided with tubes H, as and for the purpose herein shown and described.

EUGENE POWELL.
